UNITED STATES PATENT OFFICE.

EDUARD VON HÜLSEN, OF CHARLOTTENBURG, GERMANY.

TYPE-WRITING MACHINE.

SPECIFICATION forming part of Letters Patent No. 606,416, dated June 28, 1898.

Application filed May 13, 1896. Serial No. 591,388. (No model.)

To all whom it may concern:

Be it known that I, EDUARD VON HÜLSEN, of Charlottenburg, Germany, have invented certain new and useful Improvements in Stenographic Type-Writing Machines, of which the following is a specification.

This invention relates to type-writing machines; and the prime object is to provide means whereby upon depression or manipulation of a plurality of keys simultaneously the corresponding type will be successively struck, thus enabling short words and syllables to be written at a single stroke by the operator, which obviously permits increased speed. The arrangement for accomplishing this end may be broadly stated to be a type-selecting mechanism comprising means set in motion to complete a cycle of movement by the manipulation of a plurality of keys simultaneously or by the manipulation of a single key, such means being common to all the keys, and by this is meant that such means by such manipulation receives an impulse to carry it through a movement embracing all the type in the sense that in the course of and by reason of such movement any type may become operative to print. The selecting mechanism also includes devices, controlled by the keys, which by coöperation with the aforesaid key-impelled means effect a selection of type corresponding with the keys struck. Thus the number of type selected for printing by a single stroke of the hand or hands of the operator is only dependent on the number of keys simultaneously manipulated, for in every instance the key-operated means is impelled to complete a cycle of movement which embraces all the keys. The type-selecting is accompanied by a printing operation, which is dependent upon co-operation of the above-mentioned elements of the type-selecting mechanism.

In one mode of carrying out the above-stated idea I arrange the type on a carrier, (which may be a wheel or other movable support,) so that in a single rotation of the type-wheel or corresponding movement of a different form of carrier the type will be brought successively to printing position. By reason of manipulation of one or any number of keys of the machine such revolution or corresponding complete movement of the type-

carrier would ensue in the absence of any obstruction; but a yielding form of connection between the type-carrier and the keys is provided to absorb the movement incident to manipulation of a key or keys when the type-wheel is obstructed. By such an arrangement it will be seen that when a key or keys are manipulated, if the rotation of the type-wheel does not immediately ensue, a power is in any event stored whereby such rotation will eventually be completed without further manipulation of the keys. Thus by arranging suitable locking or stop devices whose operativeness is controlled by the keys the type-wheel can be checked in its rotation with any one of its type in position to print, and still upon its release its movement will continue, and it may be checked again with another type in position to print, and the complete alphabet might by this method be printed by but a single stroke, if thereby all the keys were manipulated. Instantly upon the type-wheel being checked with a type in position to print the printing-couple, one of which is, of course, the type-wheel and the other its opposed impression-bed, will be caused to coact through suitable mechanism dependent for its freedom to operate upon the actuation of means rendered operative by manipulation of the keys and operating to actuate the type-wheel-locking devices. A quick recovery or retraction of the said locking means takes place, while the separation of the printing-couple is as quickly brought about, so that the type-wheel may proceed and be locked in another position and the printing-couple again caused to coact. Incidentally the feed movement of the paper-carriage takes place, this occurring simultaneously with the separation of the printing-couple and preferably caused by the means employed to effect such separation.

The invention, as indicated above, may be embodied in a great variety of ways, all of which I shall not here attempt to illustrate or describe, confining myself to an explanation in detail of one complete form of embodiment of the invention and several modifications of parts thereof and then appending claims reciting essentials of the invention, without limitation to any one specific form of embodiment thereof.

I preferably arrange for the printing movements or coaction of the printing-couple to be effected by the momentary release of a stored power, which may be a spring-motor normally held in check through restraint of its escape-
 5 movement lever or pallet by a detent arranged to be displaced by the normally inoperative means hereinbefore referred to as actuating the type-wheel-locking device, the said means
 10 being set for operation by the manipulation of the keys. It is to be understood that such detent-displacing and type-wheel-lock-operating mechanism does not act immediately upon manipulation of the keys, but is thereby
 15 simply put in readiness to be operated whenever a type corresponding with a struck key comes to position to print. Operation of this previously-prepared mechanism is effected by the rotation of the type-wheel, which has associated with it a series of abutments relatively arranged to correspond with the location of the type, so that upon a type corresponding with a struck key coming to position to print the corresponding abutment, moving with the
 20 type-wheel, may operate the detent-displacing mechanism set by manipulation of that key, which mechanism also operates the type-wheel-locking device.
 25

The drawings which accompany and form
 30 part of this specification illustrate embodiments of the invention.

Figure I shows a perspective view of a machine constructed in accordance with the invention, some parts being omitted and some
 35 broken away for a better disclosure. Fig. II shows the keyboard in plan view with a few of

b d k s m f g p n c t w h j l r q v x y z e o a i u f l n s t r e , . : - ;
 B D K S M F G P N C T W H J L R Q V X Y Z E O A I U 2 " 3 4 5 6 7 8 9 ? !

It is to be understood that the lines of type as above given are to be placed on the periphery of the type-wheel so that when the latter stands in its normal position the first letters of the lines—viz., “b” and “B”—will be positioned in juxtaposition to the impression-bed, and the type-wheel turns in a direction to bring the other type in the lines successively to such position. Hence in a complete revolution of the type-wheel many combinations of type to make up words, syllables, and diphthongs can be obtained by reason of the arrangement of the type above explained.
 75

The arrangement of the keyboard is such that the left hand of the operator can most conveniently be employed to strike the consonants and combination of consonants occurring most frequently at the commencement of words, the thumb of the right hand to strike the vowels, and the fingers of the right hand to strike the consonants and combination of consonants occurring most frequently at the ends of words. The keys are so arranged as to permit the striking of the combination of letters which most frequently occur with the least possible changing of the positions of the hands and fingers from what

the key-bars and fragmentary views of some other parts. Fig. III shows, on an enlarged scale, a partial end elevation viewed from the left-hand side of Fig. I, certain of the parts being broken away and others omitted. Fig. IV shows a plan view of parts shown in Fig. III. Fig. V shows a plan view of parts shown at the right-hand side of Fig. I. Fig. VI shows a side view of said parts. Fig. VII shows a side view of some of said parts under a different condition. Fig. VIII shows a detail plan view of a detent-lever and coacting part seen in side elevation in Fig. III. Figs. IX, IX^a, and IX^b are side elevations illustrating the type-controlled detent-operating mechanism in different stages of its operation. Fig. X shows a perspective view of a modification. Figs. XI, XI^a, and XI^b show views of this modification similar to Figs. IX, IX^a, and IX^b. Fig. XII shows another modification of detent mechanism. Figs. XIII and XIV illustrate further modifications. Fig. XV shows a detail perspective view of a detent-lever and coacting parts seen in side elevation in Fig. III.

I have here shown the invention embodied in a machine of the type-wheel variety, and the type will be arranged in two lines on the periphery of the wheel in such order as to have those consonants which occur most frequently at the beginning of words or syllables precede the vowels, and then follows a repetition of consonants which occur most frequently at the ends of words and the letter “e.” This can best be demonstrated by giving the lines of type, thus—

may be termed the “normal” position. This normal position as the keys are arranged in Fig. II is as follows: The little finger of the left hand over “s,” the index-finger over “t,” the thumb over “w,” and the other two fingers over “g” and “h,” the thumb of the right hand over “a” or “u,” the index-finger over “n,” the little finger over “l,” and the two other fingers over “r” and “t.” The general working of the machine consists in this, that upon depression of one or several of the keys motion is imparted to the type-wheel to carry it through one complete rotation; but whenever a type corresponding with a depressed key comes to position to print the rotation of the wheel is checked and it is caused to move against the impression-bed to print and then back again to normal position, while the paper is fed and the wheel released for further rotary movement. Thus any word or syllable where letters occur successively in the type-line can be printed by one stroke of the hand, the fingers being placed on the proper keys.
 100

Passing on now to a detailed description of the form of mechanism shown in Figs. I to IX, inclusive, the numeral 26 designates a

slide or carriage mounted on rollers 25 in bearings on a suitable base, said slide carrying a cylinder 19, around which the paper is to lie and which constitutes an impression-bed for the paper. The said carriage also carries a rack 27, which will be referred to hereinafter. The numeral 1 designates the type-wheel, which is arranged over the cylinder 19, with its axis at right angles thereto, and is designed to move toward and from the said cylinder, being for this purpose mounted on a swinging journal 11, so as to rotate therewith, but capable of longitudinal movement thereon to bring the line of capital type to printing-plane. (The means for shifting the type-wheel on its journal are not here shown, as they form no part of the present invention.)

Movement of the swinging journal with the type-wheel toward the cylinder is effected through connections with a spring-motor of the following-described form and construction, reference being had more particularly to Figs. I and III: A shaft 30^a is journaled in a suitable framework adjacent to the paper-carriage and partially overhanging the same, and a toothed wheel 28, loosely mounted on said shaft, engages the rack 27, so that upon the reverse traverse of the carriage said wheel will be rotated thereby. This wheel carries a pawl 29, which engages a ratchet-wheel 30, fast on the shaft 30^a, to which is also affixed one end of a helical spring inclosed within a box 31, the outer end of the spring being fastened to the box. A gear-wheel 32 is fastened to the said box and meshes with a pinion 33 on a shaft which also carries an escapement-wheel 33^a and a cam-wheel 39 in the form of a ratchet-wheel. It will now be seen that upon the paper-carriage being run back for the commencement of a line of printing the spring-motor above described will be wound up, the rack 27 turning the gear 28, and that in turn rotating the spring-shaft 30^a through the medium of the pawl 29 and ratchet-wheel 30. The latter is prevented from turning backward by a pawl 38, pivoted to a suitable part of the framework.

The spring-motor is normally restrained by the engagement of the escapement lever or pallet 34 with the teeth of the escapement-wheel 33^a, said lever having an upstanding arm 35, which is held by engagement with an angle-lever 36 37, hereinafter referred to in connection with the key-controlled detent mechanism to regulate the operation of the motor.

Returning now to the means for imparting printing movements to the type-wheel, the periphery of the cam-wheel 39 engages the lower end of a vertically-sliding rod or bar 41, confined by a suitable guide 40 and jointed at its upper end to an arm 43, formed on or affixed to a long sleeve or rock-shaft 40^a, fitted to rotate on a spindle 42 and carrying affixed to it or formed upon it another arm 10, which at its outer end embraces the type-

wheel journal 11. Now it will be seen that when the cam-wheel 39 is turned from the position shown in Fig. III the incline of its tooth, acting against the lower end of the rod or bar 41, elevates the same, and thereby through the medium of the arm 43 rocks the sleeve 40^a and depresses the arm 10 and the type-wheel. The cam-wheel only turns one tooth at a time, and when the tooth has passed the rod 41 the parts are restored to their normal positions by a suitably-arranged spring 41^a, the type-wheel of course leaving the imprint on the paper. It may be well to describe at this point the means employed to advance the carriage, for they operate in conjunction with the mechanism just described for operating the type-wheel. The elongated sleeve or rock-shaft 40^a above mentioned has formed with it or affixed to it an arm 45, to the outer end of which is jointed a depending arm 44, whose lower end is formed as a dog or pawl 46 to engage the teeth of a ratchet-wheel 47, affixed to the toothed wheel 28. In the normal condition of parts, or that shown in Fig. III, the arm 44 stands off, so as to hold the pawl 46 clear of the ratchet-wheel 47 and permit the winding of the spring-motor. When, however, the type-wheel is moved to print in the manner above described, the said arm 44 lowers and a spring 50, bearing against its back edge, presses it into engagement with the ratchet-wheel 47, so that upon said arm being drawn up the ratchet-wheel will be turned and the carriage moved one step. The pawl 46 is thrown out of engagement with the ratchet-wheel by the coaction of an incline 48 in the arm 44 with an abutment 49, suitably arranged for the purpose.

Passing on now to the means for turning the type-wheel so as to bring any type desired to printing position, it is first to be stated, with reference more particularly to Fig. I, that the keys are mounted on vertically-sliding bars 2, which are confined in guides 2^a and upheld by springs 6, and said bars bear upon hinged frames 3, which are likewise upheld by springs 5 and are connected by equalizing-links 4. Each frame is composed of a long bar, upon which the key-bars 2 rest, and two short end bars 3^a, pivoted, as shown at 3^b, to brackets 3^c, fastened to the frame of the machine. Each key-bar rests upon the long bars of two frames or of one set of frames. There are two sets of these frames, and they are arranged at an angle to each other, and to the two innermost frames there is attached a chain 7, having two branches for connections separately with the frames and having its upper end fastened to a drum 52. (See Figs. V and VI.) This drum is affixed on a shaft 52^a and carries a pawl 53, which engages a ratchet-wheel 54, loose on said shaft and fixedly associated with a gear-wheel 55, also loose on the shaft and which meshes with a smaller gear 56, the arrangement being such that depression of any one or more of the keys effects a single revo-

lution of the small gear-wheel 56. The stud or axle of the latter is connected by a short stout spiral spring 57 with a shaft 8, mounted on suitable bearings on the frame of the machine and rotatively connected with the type-wheel journal 11 through a universal joint 9, so as to permit the swinging of said journal in the printing movements of the type-wheel.

In order to insure the turning of the type-wheel through a single revolution and no more, the shaft 8 is provided with a pin 61, which normally occupies a recess or notch in one arm 60 of a bell-crank lever, the other arm 59 of which carries a triangular pivoted abutment-piece 63, against one edge of which a pin 58 on the shaft 52^a strikes when said shaft is rotated. Rotation of the said shaft therefore disengages the horizontal arm 60 from the pin 61 by tilting the same upward, as indicated in Fig. VII; but immediately thereafter said horizontal arm returns to its original position ready to drop over the pin 61 as soon as it comes around again, the edge of said arm being beveled to permit the pin to pass under it. The spring 57 permits the independent preliminary turning of the shaft 52^a.

A spiral spring 62, connected at one end with an arm on the drum 52 and at the other end with a fixed part of the frame of the machine, exerts itself to hold the pulley in the normal position shown in Figs. V and VI, and so as soon as the key is released this spring turns the drum back to its original position, the pawl 53 sliding over the teeth of the ratchet-wheel 54 and the projection 58 tripping the triangular piece 63 by engagement with its inclined edge and passing by it to take up its original position.

The following-described mechanism is employed to establish the printing positions of the cylinder according to the key struck by checking and holding the cylinder at proper points. The key-bars all converge toward a central line extending from front to rear, as exhibited in Fig. II, and terminate below a series of hinged plates or flat arms 15, placed together side by side and individually upheld by rods 13, attached at their lower ends to the key-bars and guided at their upper ends 50 in holes in a bar 12, which also constitutes a stop to limit the downward movement of the plates or arms 15. Each of the latter has fastened to its free end a flat spring 16, (see Fig. IX,) carrying at its lower end a small abutment 17 with a beveled front and rear face or edge. A guard-plate 20 extends across in front of the series of plates 15, and when the latter are raised, as shown in Fig. IX, the engagement of the lower ends of front inclined 60 faces of the abutment 17 puts the flat springs 16 under tension. The shaft 8 carries a number of projections 18, corresponding with the plates 15 and abutments 17 and variously located around the shaft to correspond with the location of the type on the type-wheel. When any key is depressed, the lowering of the corresponding rod 13 allows the plate 15

upheld thereby to drop to the position shown in Fig. IX^b, carrying the abutment 17 below the guard 20 and allowing the spring 16 to throw it out into the path of one of the projections 18, so that the latter in rotating will press back the block by engagement with the front beveled face thereof. A rectangular frame 22 is pivotally suspended from brackets 75 on the frame of the machine, the pivots being designated by the numeral 21, and the lower bar of said rectangular frame extends behind the series of abutments 17 and is beveled for engagement with the rear beveled edges thereof, as clearly shown in Figs. IX and IX^a, so that when any one of the blocks is pressed back the frame is also moved, as shown in Fig. IX^b. Referring now again to Fig. III, there is fastened to said frame 22 a bent arm 85 or rod 23, which is coupled with a pawl or dog 51, and the latter is designed to engage a toothed wheel 24, fast on the shaft 8, but stands normally disengaged therefrom. When, however, the frame 22 is pushed back, it acts 90 through the arm 23 to draw said dog 51 into engagement with said toothed wheel, whereby the type-wheel is instantly locked. The type-wheel is thus located in a position where the type corresponding with the key struck 95 is opposite the paper, so that upon the type-wheel being moved toward the paper that type is printed. I shall presently describe how the spring-motor is released simultaneously with the locking of the type-wheel, 100 whereupon said type-wheel is moved toward the paper-bed in the manner heretofore described. As the type-wheel completes its printing movement a tooth of the wheel 33^a, acting against an arm 51^a, formed with the 105 pawl 51, disengages said pawl from the ratchet-wheel 24, so that the type-wheel may be free to rotate further to bring other type to printing position.

Proceeding now to a description of the 110 detent means heretofore adverted to, whereby the spring-motor is released, reference is to be had more particularly to Figs. III and VIII. It will be remembered that the escapement-lever 34 was described as having an upstanding arm 35. This arm projects behind a catch at the outer end of one arm 36 of a bell-crank lever pivoted to swing in a horizontal plane and having its other arm 37 projecting behind the swinging frame 22 to be acted 115 upon thereby when the latter is pushed back in the manner hereinbefore described. Thus normally the inner side of the catch of said bell-crank lever, Fig. VIII, constitutes a shoulder which prevents any movement of 120 the escapement-lever, and thus holds the motor in check; but when the frame 22 is displaced then the said detent-lever is moved so as to free the escapement. A suitably-arranged spring 37^a may be employed to restore 125 the detent-lever, and when the escapement-lever returns its arm 35 rides over the bevel of the detent-catch and takes up its position again behind said catch.

The carriage 26 is moved aside the breadth of a letter as often as the hook 46, Figs. I and III, moved up and down by the escapement 34 33^a, engages the ratchet-wheel 47 and turns it the breadth of a tooth. After a line is finished the cylinder 19 is turned the breadth of a line by a lever moved by hand, which engages a ratchet-wheel attached to the end of the cylinder. This lever and ratchet-wheel 10 are not shown in the figures.

The operation of the machine above described may be stated in a general way as follows: The depression of one or more of the keys is converted into rotative movement of the type-wheel, and the latter is stopped and locked by the encounter of a projection on the type-wheel shaft with devices brought into play by the particular key struck. The operation of these devices also effects a release 15 of the motor, so that the type-wheel is immediately moved to print. The return movement of the type-wheel after printing is accompanied by the release of its shaft and the feeding onward of the paper the breadth of 20 one letter, so that another imprint can be taken as soon as another projection on the type-wheel shaft sets the detent mechanism to work.

Referring next to the modifications, and first 30 to that illustrated by Figs. X, XI, XI^a, and XI^b, the arrangement here shown dispenses with the universal joint between the type-wheel and the shaft, and the journal and shaft of the type-wheel are all one and designated 35 8^a, and this shaft is journaled in a swinging frame 63 63^a. The hinged plates or arms 15 are the same, but springs 16^a are employed without any small blocks; but upon one of the said plates dropping its spring 16^a is carried 40 into the path of the projection 18 on the shaft and is pressed back against the frame 22, whose connection with the detent mechanism is the same as before. In this construction the shaft-locking mechanism connected with 45 the said frame 22 is dispensed with, because the downward movement of the shaft is utilized to carry its toothed wheel 24^a into engagement with a fixed pin 51^b. The downward movement of the shaft (which, by the 50 way, is produced through the same train of mechanism as before) also draws the shaft projection 18 free of the spring 16^a.

In Fig. XII an arrangement is shown wherein the pivoted plate or arm 15 is formed at its 55 free end, on the under side, with a lug 16^b, having a beveled under edge, and the shaft 8 has the projection 18^b beveled correspondingly, so that the action of these bevels against each other causes the depression of the shaft. 60 Instead of the hinged frame 22 this depression of the shaft is utilized, through a lever 37^a, pivoted at 64, to release the escapement-lever, whose arm 35 engages behind a catch 36^a at the end of said lever.

65 In Figs. XIII and XIV means are shown for employing electricity to effect the desired operations, that shown in Fig. XIII involving the

arrangement of the type-wheel shaft 8^d in an electric current, the source of electricity being designated at 65, and the projections 70 on the shaft constituting contacts to engage other contacts 16^d for closing the circuit, and thereby energizing a magnet 66, with which suitable detent and locking mechanisms can be associated. Push-buttons 2^d are employed 75 as the keys of the type-writer, so that only when a key is depressed will a circuit be closed through the corresponding contacts.

The electrical arrangement may be varied, as shown in Fig. XIV, where the shaft carries 80 a single contact-arm, which may successively engage contact-pieces 16^e arranged in its path and controlled by push-buttons, as before.

In the electrical arrangement the rotation of the type-wheel may be effected by the closing of a circuit through suitable means applied to the type-wheel shaft to rotate the same. I have not here shown certain adjuncts, such as paper-feeding means and inking devices, and any well-known or suitable 85 instrumentalities may be employed for these purposes.

Of course it will be understood that the invention disclosed is capable of embodiment in other forms than those here shown and described and is not, therefore, limited to this extent.

Having thus explained the nature of my invention and described a way of constructing and using the same, without, however, attempting to set forth all the ways in which it may be made or all the modes of its use, I declare that what I claim is—

1. In a type-writing machine, a type-selecting mechanism comprising key-operated 105 means impelled through a cycle of movement embracing all the type by manipulation of any key or a number of keys simultaneously, and devices controlled by simultaneous manipulation of the keys for successive co-operation with said key-operated means in a cycle of movement thereof to select for printing the types corresponding to the keys simultaneously manipulated.

2. In a type-writing machine, a type-selecting mechanism comprising key-operated 110 means impelled through a cycle of movement embracing all the type by manipulation of any key or a number of keys simultaneously, and devices controlled by simultaneous manipulation of the keys for successive co-operation with said key-operated means in a cycle of movement thereof to select for printing the types corresponding to the single keys simultaneously manipulated, said key-controlled 115 devices including a stop to temporarily check the key-operated means.

3. In a type-writing machine, the combination with a type-selecting mechanism, comprising key-operated means impelled through 120 a cycle of movement embracing all the type by manipulation of a key or a number of keys simultaneously, and devices controlled by simultaneous manipulation of the keys for suc-

cessive coöperation with said key-operated means in a cycle of movement thereof to select for printing the types corresponding to the single keys simultaneously manipulated, 5 of a normally-inactive printing mechanism, and connections between the same and the type-selecting mechanism for rendering said printing mechanism active by the coöperation of the key-operated means and the key-controlled devices of said selecting mechanism.

4. In a type-writing machine, the combination with a type-selecting mechanism comprising key-operated means impelled through a cycle of movement embracing all the type 15 by manipulation of a key or a number of keys simultaneously, and devices controlled by simultaneous manipulation of the keys for successive coöperation with said key-operated means in a cycle of movement thereof to select for printing the types corresponding to the single keys simultaneously manipulated, said key-controlled devices including a stop to temporarily check the key-operated means, of a normally-inactive printing mechanism, 25 and connections between the same and the type-selecting mechanism for rendering said printing mechanism active by the coöperation of the key-operated means and the key-controlled devices of said selecting mechanism.

5. In a type-writing machine, the combination with a type-selecting mechanism comprising key-operated means impelled through a cycle of movement embracing all the type 30 by manipulation of a key or a number of keys simultaneously, and devices controlled by simultaneous manipulation of keys for successive coöperation with said key-operated means in a cycle of movement thereof to select for printing the types corresponding to the single keys simultaneously manipulated, said key-controlled devices including a stop to temporarily check the key-operated means, of a normally-inactive printing mechanism, 40 and connections between the same and the type-selecting mechanism for rendering said printing mechanism active by the coöperation of the key-operated means and the key-controlled devices of said selecting mechanism, 45 and connections between the printing mechanism and the stop of the selecting mechanism for retracting said stop.

6. The combination of a type-carrier, means for moving the same, keys operatively connected with said means to put the same under stress to effect a cycle of movement of the type-carrier by manipulation of a key or keys, and key-controlled means for bringing together the printing-couple at different predetermined positions of the type-carrier in its cycle of movement, operation of said means being brought about by the movement of the type-carrier.

7. The combination of a type-wheel, means 65 for rotating the same, keys operatively connected with said means to put the same under stress to turn the type-wheel through a

single revolution by manipulation of one or more of said keys, and key-controlled means for establishing different positions of the type-wheel in such revolution.

8. The combination of a type-wheel, means for rotating the same, keys operatively connected with said means to put the same under stress to turn the type-wheel through a single revolution by manipulation of one or more of said keys, and key-controlled means for bringing together the printing-couple at different predetermined positions of the type-wheel in such revolution.

9. The combination of a type-wheel, means for rotating the same, keys operatively connected with said means to put the same under stress to turn the type-wheel through a single revolution by manipulation of one or more of said keys, and key-controlled means for establishing different positions of the type-wheel in such revolution, and for bringing together the printing-couple when such positions are established.

10. The combination of a type-wheel, means for rotating the same, keys operatively connected with said means to put the same under stress to turn the type-wheel through a single revolution by manipulation of one or more of said keys, key-controlled means for bringing together the printing-couple at different predetermined positions of the type-wheel in such revolution, operation of such means being brought about by movement of the type-wheel.

11. The combination of a type-carrier, means for moving the same, keys operatively connected with said means to put the same under stress to effect a cycle of movement embracing all the type of the type-carrier by manipulation of a key or keys, a series of projections relatively arranged to correspond with the relative location of the type on the type-carrier, and a series of abutments to coact successively with said series of projections under movement of the type-carrier by the keys, and coaction of said projections and abutments determining several printing positions of the type-carrier during one cycle of movement and bringing together the printing-couple when such positions have been established, and key-operated means controlling operative coaction of the projections and abutments.

12. The combination of a type-carrier, means for moving the same, keys operatively connected with said means to put the same under stress to effect a cycle of movement of the type-carrier embracing all the type by manipulation of a key or keys, a series of projections relatively arranged to correspond with the relative location of the type on the type-carrier, and a series of abutments to coact successively with said series of projections under movement of the type-carrier by the keys, means controlled by coaction of said projections and abutments to determine several printing positions of the type-carrier.

during one cycle of movement, and to bring together the printing-couple when such positions have been established, and key-operated means controlling operative coaction of the projections and abutments.

13. The combination of a type - carrier, means for moving the same, keys operatively connected with said means to put the same under stress to effect a cycle of movement of the type-carrier embracing all the type by manipulation of a key or keys, a normally-inactive motor operatively connected to effect coaction of the printing-couple, and key-controlled means for establishing several different positions of the type-carrier during one cycle of movement and for rendering said motor active for the purpose described.

14. The combination of a type - carrier, means for moving the same, keys operatively connected with said means to put the same under stress to effect a cycle of movement of the type-carrier embracing all the type by manipulation of a key or keys, a normally-inactive motor operatively connected to effect coaction of the printing-couple, a series of abutments relatively arranged to correspond with the relative location of the type-carrier, one or more projections to coact successively with said series under movement of the type-carrier by the keys, coaction of said projections and abutments determining several printing positions of the type-carrier during one cycle of movement and rendering the said motor active, and key-operated means controlling operative coaction of the projections and abutments.

15. The combination of a type - carrier, means for moving the same, keys operatively connected with said means to put the same under stress to effect a cycle of movement of the type-carrier embracing all the type by manipulation of a key or keys, a normally-restrained motor operatively connected to effect coaction of the printing-couple, and key-controlled means for establishing several different positions of the type-carrier, during one cycle of movement and for momentarily releasing the motor.

16. The combination of a type - carrier, means for moving the same, keys operatively connected with said means to put the same under stress to effect a cycle of movement of the type-carrier embracing all the type by manipulation of a key or keys, a normally-restrained motor operatively connected to effect coaction of the printing-couple, a series of abutments relatively arranged to correspond with the relative location of the type on the type-carrier, one or more projections to coact successively with said series under movement of the type-carrier by the keys, coaction of said projections and abutments determining several printing positions of the type-carrier during one cycle of movement and releasing the motor, and key-operated means controlling operative coaction of said projections and abutments.

17. The combination of a type-wheel, means for rotating the same, keys operatively connected with said means to put the same under stress to turn the type-wheel through a single revolution by manipulation of one or more of said keys, a normally-inactive motor operatively connected to effect coaction of the printing-couple, and key-controlled means for establishing several different positions of the type-wheel in its one revolution and for simultaneously rendering said motor active.

18. The combination of a type-wheel, means for rotating the same, keys operatively connected with said means to put the same under stress to turn the type-wheel through a single revolution by manipulation of one or more of said keys, a normally-inactive motor operatively connected to effect coaction of the printing-couple, a series of projections associated with the type-wheel and corresponding in relative location with the type, a series of key-controlled abutments to cooperate successively with said type-wheel series, and means operated by coaction of said projections and abutments to establish several predetermined positions of the type-wheel during the one revolution and render the motor active.

19. The combination of a type-wheel, means for rotating the same, keys operatively connected with said means to put the same under stress to turn the type-wheel through a single revolution by manipulation of one or more of said keys, a normally-restrained motor operatively connected to effect coöperation of the printing-couple, and key - controlled means for establishing several different positions of the type-wheel in its one revolution, and for releasing the motor.

20. The combination of a type-wheel, means for rotating the same, keys operatively connected with said means to put the same under stress to turn the type-wheel through a single revolution by manipulation of one or more of said keys, a normally-restrained motor operatively connected to effect coöperation of the printing-couple, a series of projections associated with the type-wheel and corresponding in relative location with the type, a series of key-controlled abutments to coöperate successively with said type - wheel series, and means operated by coaction of said projections and abutments to establish predetermined positions of the type-wheel and release the motor.

21. The combination of a type-wheel, means for rotating the same, keys operatively connected with said means to put the same under stress to turn the type-wheel through a single revolution by manipulation of one or more of said keys, a series of projections associated with the type-wheel and relatively located to correspond with the type, a corresponding series of key-supported abutments normally out of the path of rotation of the type-wheel projections but arranged to move into their paths when the keys are manipulated and to coact successively with them, a normally-restrained

motor to effect coaction of the printing-couple, and an escapement therefor controlled by coaction of the projections and abutments.

22. The combination of a type-wheel, means for rotating the same, keys operatively connected with said means to put the same under stress to turn the type-wheel through a single revolution by manipulation of one or more of said keys, a series of projections associated with the type-wheel and relatively located to correspond with the type, a corresponding series of key-supported abutments normally out of the path of rotation of the type-wheel projections, but arranged to move into their paths when the keys are manipulated and to coat successively with them, a normally-restrained motor to effect coaction of the printing-couple, an escapement therefor, and a detent engaging the escapement and arranged to be displaced by the coaction of the projections and abutments.

23. The combination of a type-wheel, means for rotating the same, keys operatively connected with said means to put the same under stress to turn the type-wheel through a single revolution by manipulation of one or more of said keys, a series of projections associated with the type-wheel and relatively located to correspond with the type, a corresponding series of key-supported abutments normally out of the path of rotation of the type-wheel projections but arranged to move into their paths when the keys are manipulated and to coat successively with them, a normally-restrained motor to effect coaction of the printing-couple, an escapement therefor, a detent engaging the escapement, type-wheel-locking means, and a member actuated by displacement of the key-supported abutments by the type-wheel projections to operate the type-wheel-locking means, and to displace the escapement-restraining detent.

24. In a type-writing machine, the combination with a supporting-bed for the paper; a type-wheel movable toward and from said bed; and a normally-restrained motor operatively connected with said type-wheel to move the same toward the bed: of a shaft operatively connected with the type-wheel to rotate the same, and having one or more projections; one or more movable frames associated with the keys so as to be actuated by any of them; connections between the said frames and the type-wheel shaft for turning the latter; and key-controlled means coöperating with the shaft projections to establish predetermined positions of the type-wheel and to release the motor.

25. In a type-writing machine, the combination with a supporting-bed for the paper; a type-wheel movable toward and from said bed; and a normally-restrained motor operatively connected with said type-wheel to move the same toward the bed: of a shaft operatively connected with the type-wheel to rotate the same, and having one or more projections; one or more movable frames asso-

ciated with the keys so as to be actuated by any of them; gearing associated with said shaft; a drum-and-chain connection between said gearing and the movable frames; and key-controlled means coöperating with the shaft projections to establish predetermined positions of the type-wheel and to release the motor.

26. In a type-writing machine, the combination with a supporting-bed for the paper; a type-wheel movable toward and from said bed; and a normally-restrained motor operatively connected with said type-wheel to move the same toward the bed: of a shaft operatively connected with the type-wheel to rotate the same, and having one or more projections; one or more movable frames associated with the keys so as to be actuated by any of them; gearing engaged with said shaft through a flexible connection; means of connection between the movable frames and said gearing for turning the shaft by movement of the frames; stop mechanism for positively limiting movement of the shaft to a single revolution; and key-controlled means coöperating with the shaft projections to establish predetermined positions of the type-wheel and to release the motor.

27. In a type-writing machine, the combination with a supporting-bed for the paper; a type-wheel movable toward and from said bed; and a normally-restrained motor operatively connected with said type-wheel to move the same toward the bed: of a shaft operatively connected with the type-wheel to rotate the same, and having one or more projections; one or more movable frames associated with the keys so as to be actuated by any of them; a drum carrying a pawl; a flexible connection between the said drum and the movable frames; a ratchet-wheel engaged with said pawl; gearing associated with said ratchet-wheel; flexible connections between said gearing and the type-wheel shaft; and key-controlled means coöperating with the shaft projections to establish predetermined positions of the type-wheel and to release the motor.

28. In a type-writing machine, the combination with a supporting-bed for the paper; a type-wheel movable toward and from said bed; and a normally-restrained motor operatively connected with said type-wheel to move the same toward the bed: of a shaft operatively connected with the type-wheel to rotate the same, and having one or more projections; one or more movable frames associated with the keys so as to be actuated by any of them; a drum carrying a pawl; a flexible connection between the said drum and the movable frames; a ratchet-wheel engaged with said pawl; gearing associated with said ratchet-wheel; flexible connections between said gearing and the type-wheel shaft; a latch engaged with said shaft to lock the same and having a part in the path of an abutment carried by the drum; and key-controlled means coöperating with the shaft projections to es-

tablish predetermined positions of the type-wheel to release the motor.

29. In a type-writing machine, the combination with a supporting-bed for the paper; 5 a type-wheel movable toward and from said bed; and a normally-restrained motor operatively connected with said type-wheel to move the same toward the bed: of a shaft operatively connected with the type-wheel to rotate the same, and having a plurality of projections; key-operated means for rotating said shaft; a series of key-supported movable abutments corresponding with the projections on the shaft and normally out of the paths of 10 movement of the same, said abutments arranged to drop into the paths of movement of said projections when the keys are manipulated and to be displaced from such paths of movement by the action of the projections 15 against them; and mechanism associated with said abutments and operating to lock the type-wheel in predetermined positions and to release the motor.

30. In a type-writing machine, the combination with a supporting-bed for the paper; 25 a type-wheel movable toward and from said bed; and a normally-restrained motor operatively connected with said type-wheel to move the same toward the bed: of a shaft operatively connected with the type-wheel to rotate the same, and having a plurality of projections; key-operated means for rotating said shaft; a series of key-supported arms pivoted to a fixed support having abutment- 30 pieces corresponding with the shaft projections, but normally out of position for engagement therewith; a movable frame common to all said abutment-pieces and adapted to be displaced thereby; and detent mechanisms 35 associated with said movable frame and adapted to lock the type-wheel in predetermined positions and to release the motor.

31. In a type-writing machine, the combination with a supporting-bed for the paper; 45 a type-wheel movable toward and from said bed; and a normally-restrained motor operatively connected with said type-wheel to move the same toward the bed: of a shaft operatively connected with the type-wheel to rotate 50 the same, and having a plurality of projections; key-operated means for rotating said shaft; a series of key-supported pivotal arms having pendent springs with beveled blocks for coaction with the shaft projections but normally out of position for engagement therewith; a hinged frame common to said blocks and designed to be displaced thereby; and detent mechanisms associated with said movable frame and adapted to lock the type-wheel in predetermined positions and to release the motor.

32. In a type-writing machine, the combination with a supporting-bed for the paper; 55 a type-wheel movable toward and from said bed; and a normally-restrained motor operatively connected with said type-wheel to move the same toward the bed: of a shaft opera-

tively connected with the type-wheel to rotate the same, and having a plurality of projections; depressible key-bars; connections between the same and the shaft, whereby to rotate the latter; a series of arms pivoted to a fixed support corresponding with the shaft projections and having abutments for engagement therewith; rods rising from the key-bars and supporting the said pivotal arms with their abutments clear of the shaft projections; and detent mechanisms associated with said movable frame and adapted to lock the type-wheel in predetermined positions and to release the motor.

33. In a type-writing machine, the combination with a supporting-bed for the paper; a type-wheel movable toward and from said bed; and a normally-restrained motor operatively connected with said type-wheel to move the same toward the bed: of a shaft operatively connected with the type-wheel to rotate the same, and having one or more projections; key-operated means for rotating said shaft; a toothed wheel affixed on said shaft; a locking dog or pawl to engage said wheel but normally removed therefrom; key-controlled mechanism associated with said shaft projections and with the said locking-dog, to move the latter into engagement with the toothed wheel; and key-controlled detent mechanism for releasing the motor.

34. In a type-writing mechanism, the combination with a supporting-bed for the paper; 100 a type-wheel movable toward and from said bed; and a normally-restrained motor operatively connected with said type-wheel to move the same toward the bed: of a shaft operatively connected with the type-wheel to rotate 105 the same, and having a plurality of projections; key-operated means for rotating said shaft; a series of key-controlled abutments corresponding with the projections on the shaft, but normally out of the paths of movement of the same; a toothed wheel affixed to the shaft; a movable locking-dog normally out of engagement with said wheel; connections between the series of abutments and the said dog, to move the same into engagement with the toothed wheel; and detent mechanism associated with the abutments and adapted to release the motor.

35. In a type-writing machine, the combination with a supporting-bed for the paper; 120 a type-wheel movable toward and from said bed; and a normally-restrained motor operatively connected with said type-wheel to move the same toward the bed: of a shaft operatively connected with the type-wheel to rotate the same, and having a plurality of projections; key-operated means for rotating said shaft; a series of key-supported pivotal arms having abutment-pieces corresponding with the shaft projections, but normally out of position for engagement therewith; a movable frame common to all said abutment-pieces and adapted to be displaced thereby; a toothed wheel on the type-wheel shaft; a movable lock-

- ing-dog normally disengaged from said wheel; an arm connecting said dog with the movable frame; and detent mechanism actuated by the latter to release the motor.
36. In a type-writing machine, the combination with a supporting-bed for the paper; a type-wheel movable toward and from said bed; and a normally-restrained motor operatively connected with said type-wheel to move the same toward the bed: of a shaft operatively connected with the type-wheel to rotate the same, and having a plurality of projections; key-operated means for rotating said shaft; a series of key-controlled abutments corresponding with the projections on the shaft, but normally out of the paths of movement of the same; a toothed wheel affixed to the shaft; a movable locking-dog normally out of engagement with said wheel; connections between the series of abutments and the said dog to move the same into engagement with the toothed wheel; detent mechanism associated with the abutments and adapted to release the motor; and means associated with said motor and operating to disengage the dog from the toothed wheel.
37. In a type-writing machine, the combination with a supporting-bed for the paper; a type-wheel movable toward and from said bed; and a normally-restrained motor operatively connected with said type-wheel to move the same toward the bed: of a shaft operatively connected with the type-wheel to rotate the same, and having a plurality of projections; key-operated means for rotating said shaft; a series of key-controlled abutments corresponding with the projections on the shaft, but normally out of the paths of movement of the same; a toothed wheel affixed to the shaft; an angular lever one arm of which constitutes a locking-dog to engage said toothed wheel; connections between the series of abutments and said angular lever for moving the dog into engagement with the toothed wheel; detent mechanism associated with the abutments and operating to release the motor; and a wheel associated with the latter and having inclines to act on an arm of the angular lever and disengage the dog from the toothed wheel.
38. In a type-writing machine, the combination of a bed for the paper; a type-wheel movable toward and from said bed; key-operated means for impelling said type-wheel through a complete revolution; key-controlled mechanism for establishing predetermined positions of said wheel in the course of such revolution; a spring-motor operatively connected with the movable supports of said wheel; and a key-controlled escapement for said motor.
39. In a type-writing machine, the combi-

nation of a bed for the paper; a type-wheel movable toward and from said bed; key-operated means for rotating said type-wheel through a complete revolution; key-controlled mechanism for establishing predetermined positions of said wheel in the course of such revolution; a lever engaged with the movable supports of the type-wheel; a spring-motor having a cam-wheel to actuate said lever; and a key-controlled escapement for said motor.

40. In a type-writing machine, the combination of a bed for the paper; a type-wheel movable toward and from said bed; key-operated means for rotating said type-wheel through a complete revolution; key-controlled mechanism for establishing predetermined positions of said wheel in the course of such revolution; said mechanism including a movable frame; a detent-lever engaged with said frame; an escapement-lever restrained by said detent-lever; and a spring-motor operatively connected with the movable supports of the type-wheel and normally restrained by said escapement-lever.

41. In a type-writing machine, the combination of a carriage having a bed for the paper, and a rack; a toothed wheel engaging said rack; a pawl for engaging said wheel, but normally removed therefrom; a normally-restrained spring-motor; connections between the same and said toothed wheel to wind its spring by reverse movement of the paper-carriage; a type-wheel in supports movable toward and from the paper-bed; suitable connections between said motor and the type-wheel supports, and between the motor and the said pawl; means for engaging the latter with the toothed wheel upon operation of the motor; key-actuated means for rotating the type-wheel; and key-controlled means for establishing predetermined positions of said type-wheel; and for releasing the motor.

42. In a type-writing machine, the combination of a suitable bed for the paper; a type-wheel on a journal movable toward and from the said bed; a normally-restrained motor operatively connected with said type-wheel journal; a shaft in fixed bearings and connected with the latter by a universal joint; key-actuated means for rotating said shaft; and key-controlled detent mechanism for establishing predetermined positions of the type-wheel and for releasing the motor.

In testimony whereof I have signed my name to this specification, in the presence of two subscribing witnesses, this 22d day of April, A. D. 1896.

EDUARD V. HÜLSEN.

Witnesses:

W. HAUPT,
A. VON HÜLSEN.
